CLOSURE PLUG

Charles Warren Hurley, Gaithersburg, Md., assignor to
the United States of America as represented by the
Secretary of the Army

Application July 23, 1954, Serial No. 31,583

Term of patent 14 years

(Cl. D58—10)

Fig. 1.

Fig. 2.

Fig. 3.

Fig. 4.

Fig. 5.

Figure 1 is a perspective top view of a closure plug embodying my new design;

Figure 2 is a perspective bottom view of the same;

Figure 3 is a top plan view of the same taken on an enlarged scale;

Figure 4 is a side elevational view of the same taken on an enlarged scale; and

Figure 5 is a transverse, vertical sectional view of the same taken substantially on the plane of the line 5—5 of Figure 3.

I claim:

The ornamental design for a closure plug, substantially as shown.
